UNITED STATES PATENT OFFICE

EUGENE J. RAY, OF BEVERLY, MASSACHUSETTS, ASSIGNOR TO UNITED SHOE MACHINERY CORPORATION, OF PATERSON, NEW JERSEY, A CORPORATION OF NEW JERSEY

TRIMMING MACHINE

Original application filed February 23, 1922, Serial No. 538,622. Patent No. 1,733,200, dated October 29, 1929. Divided and this application filed December 7, 1928. Serial No. 324,441.

This invention relates to trimming machines and is illustrated as embodied in a machine of the character disclosed in my co-pending application for Letters Patent of the United States, Serial No. 538,622, filed Feb. 23, 1922, now Patent 1,733,200, dated October 29, 1929, of which the present application is a division. That application discloses a machine for slugging and trimming heels. The heel-trimming portion of that machine, together with means for presenting the heels to the trimming cutter, is illustrated in this application.

It is an object of the invention to insure that shoe parts to be trimmed, illustrated as unattached heels, are presented in proper relation to the rotary cutter of a trimming machine. For this purpose, and in accordance with a feature of the invention, the work supports of the illustrated machine, which supports, as illustrated, take the form of heel clamps carried by a turret or conveyor, are each provided with a pair of jig pins arranged to enter corresponding jig holes in the shoe parts to be operated on, thereby positioning the shoe parts as they are presented to a rotary trimming tool.

It is often desired to vary the pitch to which different portions of the edge surface of a shoe part, for example a heel, are trimmed. Thus the rear portion of a heel may have a pitch greater than the side portions. Accordingly, another object of the invention is the provision in a trimming machine of improved means for varying the pitch to which the different portions of the edge of a shoe part are trimmed. With this purpose in view, the illustrated machine is provided with a trimming cutter mounted on the rotor shaft of a motor and the motor and the trimming tool are rocked, as the shoe part is moved past the cutter, about an axis which is tangent, or substantially tangent, to the edge surface to which the shoe part is to be trimmed. Considering, for example, a heel as the object to be trimmed, it will be seen that the rocking of the motor and trimming tool about an axis tangent to the edge surface of the heel will vary the angle between the edge surface and the tread sur-

face, and by suitably controlling the rocking movement a heel may be produced the edge surface of which will be perpendicular to the tread surface in the vicinity of the breast corners of the heel but which will depart substantially from the vertical at the rear of the heel. In the illustrated machine, the motor and trimming tool are stationary, except, of course, for the rotation of the trimming tool about its axis and the rocking of the motor and trimming tool referred to above, while the heel is rotated under the control of a templet so that the trimming tool operates progressively along the edge of the heel, starting at one breast corner and extending rearwardly about the rear portion of the heel and forwardly to the other breast corner.

With the above and other objects and features in view the invention will now be described with reference to the accompanying drawings which show a portion of the machine of my co-pending application, Serial No. 538,622, referred to above, to which reference may be had for a disclosure of such parts of the machine as are not illustrated herein.

In the drawings,

Fig. 1 is a side elevation of a portion of a machine embodying the invention, showing heel trimming instrumentalities and portions of a conveyor arranged to present heels thereto;

Fig. 2 is a side elevation, partly in section, of a heel clamp carried by the conveyor of Fig. 1;

Fig. 3 is a vertical sectional view of a heel and parts of the heel clamp of Fig. 2;

Fig. 4 is a front elevation of a portion of the machine showing the heel trimming instrumentalities and the conveyor for presenting the heels thereto;

Fig. 5 is a perspective view of means for rocking the motor and trimming tool to vary the pitch to which the different portions of the edge of the heel are trimmed; and

Fig. 6 is a plan view of the conveyor which presents the heels to the trimming instrumentalities of the machine, a trimming cutter being shown in operative relation to a heel which is being trimmed.

The illustrated machine is of the type provided with a conveyor which carries the work from a feeding station to one or more operating stations. In the present instance the conveyor is in the form of a rotating turret provided with a series of clamps arranged to clamp partially completed heels or heel blanks and to present them to a trimming station where their edges are trimmed by a rotary cutter.

The machine is provided with a main frame 20 of a box-like construction having an up-standing part 22 arranged to carry a motor 24. The frame 20 carries below its top a series of stationary cam track members 26 and movable cam track members 28, 30, as shown in Fig. 6. Journaled in bearings carried by the frame of the machine is an upright shaft 32 (Figs. 1, 4 and 6) upon which is mounted a conveyor or turret 34 shown as provided with three work support carrying arms. Each of these arms is provided with a stud shaft 36 upon which is journaled an arm 38 provided with an enclosed spring 40 (Fig. 6) tending to rock it away from the shaft 32. Each shaft 36 serves also as the fulcrum for a lever 42, one arm of which is provided with a roll 41 co-operating with the cam tracks 26, 28, 30 and the other arm of which is provided with a gear segment 44 meshing with a pinion 46 (Figs. 1, 4 and 6) with which each of a series of heel clamps 47 is provided. Each of these clamps (best shown in Figs. 1, 2 and 3) comprises a bracket 48 formed rigid with the corresponding arm 38 and carrying a rod 50 having a clamping member 52 slidably mounted upon the upper end thereof. Each bracket 48 is also connected to its clamping member 52 by a toggle 54 provided with a handle 56 as illustrated in Fig. 2, by means of which clamping pressure may be applied or released.

Rigid with each pinion 46 and with a shaft 57 journaled in each arm 38 is a templet 58 shaped in accordance with the desired contour of the heels to be trimmed and having rigidly connected thereto a sleeve 60 in which telescopes a second sleeve 62 provided at its upper end with a work receiving or seat portion 64 the shape of which will depend upon the character of work to be handled. In the illustrated machine this part 64 is particularly adapted to receive heels H which are to be used upon shoes having short soles, that is soles which extend rearwardly only part way from the heel breast line to the rear of the heel, and are accordingly formed each with a break or shoulder shown at 68 (Fig. 3), and each part 64 is provided with a correspondingly shaped shoulder. To control the position of the heel H upon the work support, the seat portion 64 is provided with a pair of jig pins 70 (Fig. 3) arranged to co-operate with corresponding jig holes formed in the heels H so as to insure the uniform

positioning of the heels in the machine. Each clamp member 52 is provided with a work engaging plate 72 rotatably connected thereto as by ball bearings 74. A stiff spring 76 is housed within sleeves 60 and 62, serving to press the work firmly against the plate 72 when the toggle 54 is in clamping condition.

A roll 78 (Figs. 1 and 6) is provided, mounted on a stationary axis, at each operating station to co-operate with the templet 58 so as to move the heel being trimmed in a path corresponding to the form of the templet 58 as the heel is rotated through the gearing 44, 46 about the axis of the gear 46, which axis passes through the central portion of the heel.

Surrounding each shaft 57 is a spring 80 anchored at its upper end to a collar 82 rigidly connected to the shaft 57 (Fig. 4) and at its lower end to the arm 38. Thus as a gear segment 44 rotates the corresponding pinion 46 in one direction, the spring 80 is tensioned and will store energy to rotate the pinion 46 in the opposite direction later in the operation of the machine.

The conveyor 34 is given a step-by-step motion by mechanism which will now be outlined. A vertical shaft 90 (Fig. 4) driven from the motor 24 is arranged to drive a vertical shaft 114 (Figs. 4 and 6) by suitable mechanism the details of which form no part of the present invention and are not illustrated herein. For a full disclosure of this mechanism reference may be had to the application previously referred to and having Serial No. 538,622.

The driving mechanism for the conveyor 34 is so arranged that the conveyor remains at rest during the trimming operation. While the conveyor is at rest the operator removes from that heel clamp 47 which is then located at the loading station L (Fig. 6) a heel which has been trimmed and places a fresh heel in that clamp, utilizing the jig pins 70 to insure the correct positioning of the heel. After this the conveyor 34 is started and a heel which is to be trimmed is carried to the trimming station T, whereupon the conveyor 34 again comes to rest and is held in position for the trimming operation.

Mechanism which will now be described is provided to control the rocking of the arms 42 thus to control the presentation of the work to the fastening inserting and trimming devices. Mounted upon the shaft 114 are a pair of cams 170, 172 (Fig. 6). The cam track member 28 is rigidly connected with a rock shaft 174 having bearings in the frame of the machine and provided with an arm 176 to which is secured a spring 178 tending to rock the shaft in a counterclockwise direction as viewed in Fig. 6. The rock shaft 174 is also provided with a rearwardly extending arm 180 carrying a roll 181 held by the spring 178 in contact with the cam 170.

Movement of the cam 170 in the direction of its arrow (Fig. 6) will rock the arm 28 in the direction of its arrow thus rocking the arm 42, which controls the work then at the slugging station S, in a clockwise direction and rotating the heel at the slugging station in a counterclockwise direction. As the heel rotates the templet 58 is maintained in contact with the roll 78 by the action of the spring 40 so that the slugs are inserted in a line parallel to the periphery of the heel.

While one heel is being slugged another heel at the trimming station T is being trimmed. This heel is rotated by the spring 80 of its clamp 47, which spring was tensioned during the slugging of that heel in the preceding cycle of operation of the machine. As this spring rotates the heel, its templet 58 contacts with the roll 78 at the trimming station T to position the heel, the rotation of the heel being controlled through the corresponding arm 42 and the cam track member 30. As the cam 28 advances to rotate the heel at the slugging station, the cam 30 is retracted to permit rotation in the opposite direction of the heel at the trimming station. For this purpose the cam track member 30 is rigidly connected through a rock shaft 182 to an arm 184 provided with a spring 186 anchored to the frame 20 and tending to move it in a counterclockwise direction as viewed in Fig. 6. The extremity of the arm 184 is connected by a link 188 to an arm 190 secured to a rock shaft 192, the latter being provided with an arm 194 carrying a cam roll 195 held by the spring 186 in contact with the cam 172. Thus the rotation of the heels at the trimming station is controlled by the rotation of the cam 172.

Adjacent to the trimming station T the frame of the machine carries a bracket 450 (Figs. 1, 4 and 5) provided with arcuate ways 452 arranged to receive arcuate flanges formed upon a co-operating bracket 454 carried by the casing of a motor 456. Directly connected to the rotor shaft of the motor 456 is a rotary trimming tool 458.

The bracket 454 carries a gear segment 460 meshing with a gear segment 462 carried by a shaft 464 having bearings in the bracket 450 and in another upstanding part 451 of the frame of the machine. Rigidly connected to shaft 464 is an arm 468 connected by a link 470 to one arm of a bell crank lever 472 suitably fulcrumed to the frame of the machine and having its other arm connected by a link 474 with one arm of a similarly fulcrumed bell crank lever 476 the other arm of which carries a roll 478 co-operating with a cam 480 carried by the shaft 114. A spring 481 secured to the bell crank lever 476 serves to hold the roll 478 in engagement with the cam 480. Thus rotation of the shaft 114, which takes place once during each cycle of operation of the machine, automatically

rocks the motor 456 and the trimming tool 458 in a manner dependent upon the form of the cam 480, to vary the pitch of the different portions of the edge surface of the heel as may be desired.

Preferably, and as illustrated, the axis about which the gear segment 460, the motor 456 and the trimming tool 458 are rocked is tangent to the edge surface to which the heel in the clamp 47 at the trimming station T is to be trimmed. This permits the pitch to be varied (for example, to be increased at the rear part of the heel) with a minimum deviation between the horizontal cross-section of the heel and the form of the templet 58.

In the operation of the machine the operator places a heel which is to be trimmed upon the work receiving portion 64 of that heel clamp 48 which is located at the loading station L and clamps the heel in position by means of the toggle 54. At this time the conveyor 34 is at rest. The conveyor 34 is then moved to transfer the newly presented heel to the slugging station S, the heel which was slugged during the preceding cycle of operation being transferred to the trimming station T. The conveyor 34 then comes to rest. The heel which is located at the trimming station T is then rotated by rocking movement of the arm 42 under the control of the cam 172 and transmitted through the rock arms 194, 190, the link 188, the rock arm 184 and the cam track member 30. During its rotation the heel is also moved toward the trimming cutter 458 by the spring 40 and away from the trimming cutter against the compression of that spring under the control of the templet 58 and the roll 78 against which it bears. As the cutter 458 trims the sides and rear of the heel, the motor 456, together with the cutter 450, is rocked by the mechanism shown in Fig. 5 about an axis tangent to the edge surface of the heel in the clamp 48, thereby varying the pitch of the heel and producing, for example, a heel the edge surface of which is substantially at right angles to the tread surface in the vicinity of its breast corners but which is somewhat inclined at the rear of the heel.

Having described my invention, what I claim as new and desire to secure by Letters Patent of the United States is:

1. A trimming machine having, in combination, a rotary trimming tool and a conveyor arranged to transfer shoe parts to and from said trimming tool, the conveyor being provided with jig pins arranged to enter corresponding jig holes in the shoe parts to position the shoe parts as they are presented to the rotary trimming tool.

2. A heel trimming machine having, in combination, a rotary trimming tool and a conveyor arranged to transfer unattached heels to and from said trimming tool, the conveyor being provided with jig pins ar-

ranged to enter corresponding jig holes in the heels to position the heels as they are presented to the rotary trimming tool.

3. A heel trimming machine having, in combination, a rotary trimming tool, a heel support provided with one or more jig pins arranged to enter corresponding jig holes formed in the heels which are to be trimmed to control the position of the heels as they are presented to the trimming tool, and means for causing relative movement of the trimming tool and the heel support to cause the trimming tool to trim surplus material from the edge surface of the heel on the support.
4. A heel trimming machine having, in combination, a rotary trimming tool, a heel support provided with one or more jig pins arranged to enter corresponding jig holes in the heels to be trimmed to control the position of the heels as they are trimmed by the rotary tool, means for clamping a heel on the support, and gearing for causing relative movement of the trimming tool and the heel support to cause the tool to trim surplus material from the heel clamped on the support.

5. A machine for trimming the edges of shoe parts having, in combination, a rotary trimming tool, a support for a shoe part provided with one or more jig pins arranged to enter corresponding jig holes formed in the shoe part to control the presentation of the shoe part to the trimming tool, means for causing relative movement of the trimming tool and the support to cause the trimming tool to trim surplus material from the edge surface of the shoe part on the support, and means for rocking the motor and the trimming tool to vary the pitch to which the different portions of the edge of the shoe part are trimmed.

6. A heel trimming machine having, in combination, a rotary trimming tool, a heel clamp having one or more jig pins arranged to enter corresponding jig holes in a heel to control the position thereof, and means for moving the heel clamp in a path corresponding to the contour to which the heel is to be trimmed as the heel is trimmed by the rotary tool.

7. A heel trimming machine having, in combination, a rotary trimming tool, a heel support having one or more positioning surfaces arranged to engage corresponding positioning surfaces on the heels to be trimmed to control the position of the heels on the support, a templet connected to the heel support to control the movement thereof, and means for rotating the templet, the heel support and the heel carried thereby to present the edge surface of the heel to the trimming tool.

8. A heel trimming machine having, in combination, a rotary trimming tool, a heel support having one or more jig pins ar-

ranged to enter corresponding jig holes in the heel to control the position thereof, a templet connected to the heel support to control the movement thereof, and means for rotating the templet, the heel support and the heel carried thereby to present the edge surface of the heel to the trimming tool.

9. A machine for trimming the edges of shoe parts having, in combination, a motor, a trimming tool mounted on the rotor shaft of the motor, a support for the shoe part to be operated upon, means for rotating the support to present different portions of the edge of the shoe part carried thereby to the trimming tool, a carrier for the support constructed and arranged to move the support to and from trimming position, and means for rocking the motor and the trimming tool to control the pitch to which the different portions of the edge of the shoe part are trimmed.

10. A machine for trimming shoe parts having, in combination, a motor, a trimming tool mounted on the rotor shaft of the motor, a clamp constructed and arranged to hold the shoe part to be operated upon, means for moving the clamp to present different portions of the edge of the shoe part carried thereby to the trimming tool, and toothed gearing for rocking the motor and the trimming tool to control the pitch to which the different portions of the edge of the shoe part are trimmed.

11. A heel trimming machine having, in combination, a motor, a trimming tool mounted on the rotor shaft of the motor, a heel support, and means to rotate the heel support about an axis passing through the heel constructed and arranged to present both sides and the rear of the heel to the trimming tool in a single operation so that the trimming tool operates continuously from one breast corner around the rear of the heel to the other breast corner.

12. A machine for trimming the edges of shoe parts having, in combination, a motor, a trimming tool mounted on the rotor shaft of the motor, a support for the shoe part the edge of which is to be trimmed, a templet of a form corresponding to the contour to which the shoe part is to be trimmed and arranged to control the position of the support as the support is moved, and means for rocking the motor and the trimming tool to control the pitch to which the different portions of the edge of the shoe part are trimmed.

13. A machine for trimming the edges of shoe parts having, in combination, a motor, a trimming tool mounted on the rotor shaft of the motor, a support arranged to carry a shoe part the edge of which is to be trimmed, means to move the support to present different portions of the periphery of the shoe part carried thereby to the trimming tool, and means for rocking the motor

and the trimming tool about an axis substantially tangent to the edge surface of the shoe part to be trimmed to control the pitch to which the different portions of the edge 5 of the shoe part are trimmed.

14. A machine for trimming the edges of shoe parts having, in combination, a motor, a trimming tool mounted on the rotor shaft of the motor, a support arranged to carry a shoe 10 part the edge of which is to be trimmed, means to move the support to present different portions of the periphery of the shoe part carried thereby to the trimming tool, a cam, and connection between the cam and the 15 motor arranged to rock the motor and the trimming tool about an axis substantially tangent to the edge surface of the shoe part to be trimmed to control the pitch to which the different portions of the edge of the shoe 20 part are trimmed.

15. A heel trimming machine having, in combination, a heel support, a motor, a trimming tool mounted on the rotor shaft of the motor, means for causing relative movement 25 of the heel support and the motor arranged to present a heel carried by the support to the trimming tool and to cause the tool to trim the edge of the heel progressively from one breast corner rearwardly about the back 30 of the heel and then forwardly to the other breast corner, and means for rocking the motor to control the pitch to which the different portions of the edge surface of the heel are trimmed.

35 16. A heel trimming machine having, in combination, a rotary trimming tool, a support constructed and arranged to hold an unattached heel, means for rotating the heel support to present the edge surface of a heel carried thereby to the trimming tool, and automatically controlled, power actuated means for rocking the axis of rotation of the trimming tool to control the pitch to which the different portions of the edge surface of the heel are trimmed.

40 17. A heel trimming machine having, in combination, a motor, a trimming tool mounted on the rotor shaft of the motor, a heel support, means for rotating the heel support to present the edge surface of a heel carried thereby to the trimming tool, and means for rocking the motor to control the pitch to which the different portions of the edge surface of the heel are trimmed.

45 18. A heel trimming machine having, in combination, a shaft, a rotary trimming tool mounted thereon, a heel support, means for rotating the heel support to present the edge surface of a heel carried thereby to the trimming tool, a cam, and connections from the cam to the shaft of the trimming tool to control the pitch to which the different portions of the edge surface of the heel are trimmed.

50 19. A heel trimming machine having, in combination, a motor, a trimming tool mount-

ed on the rotor shaft thereof, a heel clamp, means for rotating the heel clamp to present the edge surface of a heel carried thereby to the trimming tool, a templet of a form corresponding to the contour to which the heel carried by the clamp is to be trimmed and arranged to control the heel clamp as the latter rotates, and means for rocking the motor to control the pitch to which the different portions of the edge surface of the heel are 70 trimmed.

20. A heel trimming machine having, in combination, a motor, a trimming tool mounted on the rotor shaft thereof, a heel clamp, means for rotating the heel clamp about an axis passing through a heel carried thereby to present the sides and rear of the heel to the trimming tool, and a templet of a form corresponding to the contour to which the side and rear of the heel carried by the clamp are to be trimmed and arranged to control the heel clamp as the latter rotates.

21. A heel trimming machine having, in combination, a shaft, a trimming tool mounted thereon, a heel support, means for rotating the heel support to present the edge surface of a heel carried thereby to the trimming tool, a templet of a form corresponding to the contour to which the heel carried by the support is to be trimmed and arranged to control the heel clamp as the latter rotates, a cam, and connections from the cam to the shaft of the trimming tool to control the pitch to which the different portions of the edge surface of the heel are trimmed.

22. A heel trimming machine having, in combination, a motor, a trimming tool mounted on the rotor shaft thereof, a heel clamp, means for rotating the heel clamp to present the edge surface of a heel clamped therein to the trimming tool, a templet of a form corresponding to the contour to which the heel carried by the clamp is to be trimmed and arranged to control the presentation of the heel to the trimming tool as the heel clamp rotates, a cam, and connections from the cam to the motor arranged to rock the motor as the heel clamp rotates thereby to control the pitch to which the different portions of the edge surface of the heel are trimmed.

23. A heel trimming machine having, in combination, a motor, a trimming tool mounted on the rotor shaft of the motor, a heel support, means for rotating the heel support to present the edge surface of a heel carried thereby to the trimming tool, and means for rocking the motor about an axis substantially tangent to the edge surface of the heel carried by the support to control the pitch to which the different portions of the edge surface of the heel are trimmed.

24. A heel trimming machine having, in combination, a motor, a trimming tool mounted on the rotor shaft thereof, a heel clamp, means for moving the heel clamp to present

the edge surface of a heel carried thereby to the trimming tool, and means for rocking the motor about an axis tangent to the edge surface of the heel carried by the support, to control the pitch to which the different portions of the edge surface of the heel are trimmed.

25. A heel trimming machine having, in combination, a shaft, a rotary trimming tool mounted thereon, a heel support, means for rotating the heel support to present the edge surface of a heel carried thereby to the trimming tool, a cam, and connections from the cam to the shaft of the trimming tool arranged to cause the cam to rock the shaft about an axis tangent to the edge surface of the heel carried by the support to control the pitch to which the different portions of the edge surface of the heel are trimmed.
- 20 26. A heel trimming machine having, in combination, a motor, a trimming tool mounted on the rotor shaft thereof, a heel clamp, means for rotating the heel clamp to present the edge surface of a heel carried thereby to the trimming tool, a templet of a form corresponding to the desired contour of the heel being trimmed and arranged to control the heel clamp as the latter rotates, and means for rocking the motor about an axis tangent to the edge surface of the heel in the clamp to control the pitch to which the different portions of the edge surface of the heel are trimmed.

In testimony whereof I have signed my name to this specification.

EUGENE J. RAY.
